DEVICE FOR STRAIGHTENING THE WELTS OF SOCKS PREPARATORY TO A BOARDING OPERATION

John W. Glaze, Jr., Charlotte, N.C., assignor to Auto-board Corporation, Charlotte, N.C., a company of North Carolina

Filed Mar. 1, 1962, Ser. No. 176,666

Claims priority, application Great Britain Mar. 17, 1961
8 Claims. (Cl. 223—60)

This invention appertains to devices for straightening the welts of socks preparatory to the latter being boarded by passage through a boarding or finishing machine or apparatus.

As well known to those acquainted with the art concerned, a boarding machine or apparatus, for either pre-boarding or post-boarding, is one wherein boarding forms, on to which can be pulled stockings, half hose, socks or like articles to be treated, are caused to travel in a prescribed path through a boarding chamber in which the individually supported articles are subject to a fluid treatment phase for the purpose of setting them to the shape of the forms. The fluid treatment phase may involve the supply of steam into or/and the exhaustion of steam from the boarding chamber, although it may alternatively consist of guiding on to the forms a flow of air issuing from a blower and heated by steam coils. In such a boarding or finishing machine or apparatus, moreover, the forms are mounted either on a carriage or on a conveyor which is arranged to travel through an elongated opening into the boarding chamber.

One particular form of automatic boarding or finishing machine is described in U.S. Patent application Serial No. 15,132 filed March 15, 1960, now Patent No. 3,054,542, granted September 18, 1962.

The term "socks" hereinafter employed in defining and exemplifying this invention is used in a generic sense to include so-called half hose and any other appropriate kind of knitted articles of footwear in connection with which the devices provided by this invention can advantageously be adopted.

In this regard, however, it is to be clearly understood that the devices constituting this invention are only applicable for use when boarding socks made without elastic or equivalent tops. Now heretofore when such un-elasticised socks are pulled on to boarding forms the tops tend to balloon out or/and curl outwardly—a condition which naturally precludes satisfactory boarding.

The object of the present invention is to provide for use in conjunction with a boarding or finishing machine or apparatus, a simple, efficient and economically produced device adapted to act on and to stretch or/and uncurl the welts of socks previously pulled on to forms in such a way as to make these welts lie flat against and conform closely to the shapes of the said forms prior to the latter moving into the boarding chamber.

It is in this sense that the term "welt straightening" is used in this specification.

The device constituting the invention comprises in combination, a pair of welt straightening rollers which are covered with a relatively soft, yielding material and are so arranged that a traveling form having a sock pulled on to it and just prior to entering the treatment chamber of a boarding machine or apparatus is passed edgewise between the said rollers, and means for rotating the rollers suchwise as to cause them to stroke the welt of the sock at opposite sides of the form and in a direction away from the foot of the article. Any tendency of the welt to balloon out or/and curl outwardly is, therefore, counteracted by a "straightening" of the welt in the sense herebefore defined.

If, as will usually be the case, the traveling boarding

2

forms are vertically disposed with their shaped foot portions uppermost, then the welt straightening rollers will stroke each sock welt downwardly thereby to some extent stretching it when conforming it to the corresponding form.

In any event, the plane of a flat form passing between the two welt straightening rollers is parallel to the axes of the latter.

Thus, where the boarding forms are vertical, the axes of the rollers may advantageously be contained in a common horizontal plane.

To enable the invention to be more clearly understood and readily carried into practical effect, specific constructional examples of the improved welt-straightening device will now be described with reference to the accompanying diagrammatic drawings, wherein,

FIGURE 1 is a front view of one form of the said device shown mounted upon a boarding chamber,

FIGURE 2 is a side view of the same as seen in the direction of the arrow A in FIGURE 1,

FIGURE 3 is a detail perspective view illustrating the mounting bracket of the left-hand one of the two roller units,

FIGURE 4 is a detail plan view of one of the blocks whereby a vertical guide rod and a vertical rotary screw associated with the right-hand roller unit are mounted,

FIGURE 5 is a detail plan view of the carrier block for the motor bracket of the said right-hand unit, and

FIGURE 6 is a general perspective view of a modified form of the welt-straightening device.

Like parts are designated by similar reference characters throughout the drawings.

Referring to the drawings, it will be seen that the device in each of the two examples includes a pair of welt straightening rollers 1 and 2. These are so arranged that a traveling form, such as that indicated at F in FIGURE 6 and having a sock such as S pulled on to it, and just prior to passing through a narrow vertical entry aperture 3 in one wall of a boarding chamber 4, is passed edgewise between the said rollers. The device also includes electric motors 5 and 6 for driving the rollers 1 and 2 in respectively opposite directions, indicated by the arrows B and C in FIGURE 1. In this way, the rollers 1 and 2 are caused to stroke the welt W of the sock S at opposite sides of the form F in a downward direction away from the foot of the sock.

Preferably, the rollers 1 and 2 are covered with lambs wool since this is a very soft and yielding material capable of moving transversely over a sock welt with a gentle brushing action whilst at the same time lightly and yieldingly pressing the welt against opposite sides of a form. Such material, therefore, is kind to and cannot damage the knitted fabric of a sock. It is, however, within the scope of the invention to cover the rollers with felt, cloth or any other appropriate soft, yieldable material which will not distort the individual fibres in a sock.

The two welt straightening rollers 1 and 2 are driven independently—each from its separate electric motor. The motors 5 and 6 are preferably of the low speed gear type.

In the specific example illustrated in FIGURES 1 and 2, the axis of each of the electric motors 5 and 6 is disposed at right angles to the rotational axis of the corresponding roller, in which instance each roller spindle 7 is driven from the motor spindle 8, e.g. through worm gearing 9, 10. Any other appropriate intermediate gearing may, however, be employed. In the modification illustrated in FIGURE 6 the welt straightening rollers 1 and 2 and their respective motors 5' and 6' are co-axial.

In each of the two illustrated examples, a common bracket or support is provided to carry each motor and the roller driven thereby.

In accordance with an important feature of the invention, provision of any suitable character may be made for simultaneous adjustment of the two rollers together with their motors in a direction either towards or away from the foot portions of the boarding forms F passing edgewise between them so that the operator can adjust the device for the particular length of sock being boarded. Manually operable rotary screw means may conveniently be provided for this purpose.

Additionally, the rollers are preferably so mounted that they can be laterally or otherwise adjusted relatively in order to vary the pressure exerted thereby against opposite sides of a sock passing therebetween. This additional provision would, in fact, be essential in cases where socks vary greatly in weights, one setting being necessary for very heavy socks and another for light socks.

Constructional examples of the features broadly described in the last two paragraphs, and associated features will now be described in greater detail with reference to FIGURES 1-5.

As will be seen, each of the two independent electric motors 5 and 6 is supported upon a mounting bracket 11 of angular form which also carries the associated welt straightening roller 1 or 2. Each of the brackets 11 is rigidly secured, by screws 12, upon the front of a rectangular carrier block 13. Although the two carrier blocks 13 are generally similar in form, one is left-hand and the other right-hand. To enable the brackets 11 to be adjusted laterally in relation to the carrier blocks 13, each such bracket has formed therein a pair of horizontal slots 14 through which the shanks of the screws 12 extend. Each carrier block 13 has formed therein at one side thereof a recess 15 of rectangular cross-section (see FIGURE 5) through which extends a plain vertical guide rod 16 of circular cross-section. The block 13, and hence the entire roller unit comprising the relevant welt straightening roller and its electric motor, is freely slideable up and down the corresponding guide rod 16. At its opposite ends, each vertical guide rod 16 is formed with co-axial eccentrics 16a which are mounted to turn in bushed bearings 17 provided in a pair of small blocks 18 and 19 attached to the relevant wall of the boarding chamber 4. The purpose of these eccentrics will be hereinafter explained. Moreover, each carrier block 13 has formed therethrough, parallel to the recess 15, a bore 20 which is suitably tapped to receive a vertical rotary screw 21. This screw, which is parallel to the corresponding guide rod 16, has suitably reduced plain portions which are freely rotatable in bearings 22 and 23 provided in the upper and lower fixed blocks 18 and 19 respectively. Hence, the two rotary screws 21, whilst rotatable in their bearings, are both prevented from any axial movement. At their upper ends the reduced plain portions of the rotary screws 21 extend above the upper blocks 18 and have secured thereto chain wheels 24 around which is passed a chain 25. Both chain wheels 24 are simultaneously rotatable by the turning of a handwheel 26 secured to one of the screws 21. Thus, according to the direction in which this handwheel 26 is turned, the mounting brackets 11, the motors 5 and 6 and the welt straightening rollers 1 and 2 will all be raised or lowered, according to requirements. Thus, as will be appreciated, the tapped blocks 13 are in the nature of nuts which are raised and lowered according to the direction in which the screws 21 are rotated. Instead of chain wheels and a chain, pulleys and a belt or any equivalent means may be provided for rotating the screws 21.

To vary the pressure or tension between the rollers 1 and 2, the guide rods 16 with their eccentrics 16a are made turnable within the bearings 17, the effect of such turning movements being to pivot the blocks 13, and hence the entire roller units, about the rotary screws 21, thereby either pulling the rollers nearer together to tighten them or pushing them slightly away from one

another to slacken them. To enable them to be turned, the eccentric rods 16 are furnished at their lower ends with levers 27. These levers are turned toward each other to increase and away from each other to decrease the roller tension. A screw 28 extending through one of the horizontal slots 14 in the corresponding mounting bracket 11 is arranged to impinge on each of the rods 16 and is used to lock the rod in position after an adjustment. The modified form of the device illustrated in FIGURE 6 is of a simpler and less developed form. In this case the motor brackets 29 are simply slideable up and down vertical guide rods 16' to set the roller units heightwise.

The action of the device of this invention is continuous and, as explained, takes place as the forms F are passing seriatim between the rollers. Although the rollers are preferably set to run continuously whenever the boarding or finishing machine or apparatus is in operation, they could be arranged to run only at such times as they are in contact with a sock.

The entire device may, as shown, be designed as a unitary attachment adapted for ready application to the exterior of a wall of the boarding chamber 4 of the machine—in line with the opening 3 in this wall through which the travelling forms F pass into the interior of the said chamber.

I claim:

1. In a boarding machine wherein vertically disposed boarding forms with their foot portions uppermost, and capable of individually supporting knitted socks having un-elasticated welts, are caused to travel through a vertical entrance aperture into a boarding chamber in which said socks are subject to a fluid treatment phase, a welt-straightening device comprising, in combination, a pair of welt-straightening rollers covered with a relatively soft, yielding material, said rollers being arranged together side by side at a location intermediate the foot portions and the opposite ends of the travelling forms, immediately in advance of said vertical entrance aperture and with their axes in a common horizontal plane at opposite sides of and substantially parallel to the vertical plane in which the forms travel, and means rotating the rollers in opposite directions whereby adjacent portions of the rollers move downwards together, away from the foot portions of the forms, suchwise as to enable the rollers to engage and stroke each sock welt downwardly, thereby causing it to lie flat against and conform to the corresponding form as the latter passes edgewise between the rollers.

2. In a boarding machine wherein boarding forms, capable of individually supporting knitted socks having un-elasticated welts, are caused to travel through an entrance aperture into a boarding chamber in which said socks are subject to a fluid treatment phase, a welt-straightening device comprising in combination a pair of welt straightening rollers covered with a relatively soft, yielding material, said rollers being arranged together at a location intermediate the foot and the opposite ends of the travelling forms, immediately in advance of said entrance aperture and with their axes at opposite sides of and substantially parallel to the plane in which the forms travel, two separate electric motors for driving the respective rollers independently in opposite directions whereby adjacent portions of the rollers move together in a direction away from the foot portions of the sock-supporting forms suchwise as to enable the rollers to engage and stroke opposite sides of, and so flatten, the welt of a sock supported on a form passed edgewise between the rollers, a common bracket carrying each electric motor and the roller driven thereby, and manually controlled means engaged with said brackets and operable for simultaneously adjusting the two rollers together with their motors in a direction either towards or away from the foot portions of the forms, for the purpose specified.

3. The combination according to claim 2, which in-

cludes manually operable rotary screw means for simultaneously adjusting the two rollers and their motors.

4. The combination according to claim 2, wherein the rollers are mounted for relative movement to increase or decrease the tension therebetween, and means are provided for effecting adjustment of said rollers in this sense in order to vary the pressure exerted thereby against opposite sides of a board-supported sock passing therebetween.

5. The combination according to claim 2, wherein the axis of each electric motor is disposed at right angles to the rotational axis of the corresponding roller, and the spindle of the latter is adapted to be driven from the motor spindle through gearing.

6. In a boarding machine wherein vertically disposed boarding forms with their foot portions uppermost, and capable of individually supporting knitted socks having un-elasticated welts, are caused to travel through a vertical entrance aperture formed in a wall of a boarding chamber in which latter said socks are subject to a fluid treatment phase, a welt-straightening device comprising, in combination, a pair of welt-straightening rollers covered with a soft, yielding material, said rollers being arranged together side by side at a location intermediate the foot portions and the opposite ends of the travelling forms, in advance of said vertical entrance aperture and with their axes in a common horizontal plane at opposite sides of and substantially parallel to the vertical plane in which the forms travel, two separate electric motors for driving the respective rollers independently in opposite directions whereby adjacent portions of the rollers move together in a direction away from the foot portions of the forms suchwise as to enable the rollers to engage and stroke opposite sides of, and so flatten, the welt of a sock supported on a form passed edgewise between the rollers, a

5

10

15

common bracket structure carrying each electric motor and the roller driven thereby, each such bracket structure having formed therethrough a vertically tapped bore and, parallel with the latter a recess, two plain vertical guide rods extending through the said recesses and up and down

which said common bracket structures are slideable, blocks attached to the aforementioned wall of the boarding chamber and in which the ends of said guide rods are supported, bearings mounted in said blocks, two vertical

10 rotary screws which extend through the tapped bores in the common bracket structures and have their ends freely

rotatable in the said bearings in the blocks, and manually

controlled means operable for simultaneously rotating the

screws and so adjusting the two rollers and their motors

in a direction towards or away from the foot portions of

the forms, for the purpose specified.

7. The combination according to claim 6, wherein the ends of the vertical guide rods are provided with co-axial eccentrics mounted to turn in further bearings in the

20 blocks, said rods also being furnished with levers whereby

they can be relatively turned to cause the common bracket

structures to pivot about the axes of the rotary screws,

for the purpose described.

8. The combination according to claim 7, wherein

25 screws extending through the bracket structures and im-

ping on the guide rods are provided to lock the latter

in position after an adjustment.

30

35

common bracket structure carrying each electric motor and the roller driven thereby, each such bracket structure having formed therethrough a vertically tapped bore and, parallel with the latter a recess, two plain vertical guide rods extending through the said recesses and up and down which said common bracket structures are slideable, blocks attached to the aforementioned wall of the boarding chamber and in which the ends of said guide rods are supported, bearings mounted in said blocks, two vertical

10 rotary screws which extend through the tapped bores in the common bracket structures and have their ends freely

rotatable in the said bearings in the blocks, and manually

controlled means operable for simultaneously rotating the

screws and so adjusting the two rollers and their motors

in a direction towards or away from the foot portions of

the forms, for the purpose specified.

7. The combination according to claim 6, wherein the ends of the vertical guide rods are provided with co-axial eccentrics mounted to turn in further bearings in the

20 blocks, said rods also being furnished with levers whereby

they can be relatively turned to cause the common bracket

structures to pivot about the axes of the rotary screws,

for the purpose described.

8. The combination according to claim 7, wherein

25 screws extending through the bracket structures and im-

ping on the guide rods are provided to lock the latter

in position after an adjustment.
